UNITED STATES PATENT OFFICE.

THOMAS DUNN, OF ST. CHARLES, MISSOURI.

PUMP JACK.

Application filed May 17, 1924. Serial No. 714,118.

To all whom it may concern:

Be it known that I, THOMAS DUNN, a citizen of the United States, residing at St. Charles, in the county of St. Charles and State of Missouri, have invented new and useful Improvements in Pump Jacks, of which the following is a specification.

This invention relates to a pumping apparatus, particularly to a pump jack device for association with a pump of the ordinary hand operated type, and has for its object the provision of a novel mechanism or transmission designed to be power operated and so constructed and arranged as to be clamped upon an ordinary hand pump and operatively connected with the operating rod thereof whereby to pump the water or other liquid in a rapid and efficient manner.

A very important object is the provision of a device of this character which is so constructed and arranged as to relieve the driving motor of considerable strain and thereby save wear, tear and fuel consumption.

Yet another object is the provision of a device of this character having a shock absorbing spring therein which not only operates to cushion the force of the down stroke but which also acts to assist the motor on the upstroke so that the strain on the working parts will be greatly reduced.

An additional object is the provision of a device of this character which will be simple and inexpensive in manufacture, easy to install, positive in action, efficient and durable in service, and a general improvement in the art.

With the above and other objects and advantages in view, the invention consists in the details of construction to be herein-after more fully described, claimed, and illustrated in the accompanying drawings, wherein:

Figure 1 is a side elevation of a pump equipped with my jack mechanism.

Figure 2 is an elevation at right angles to Figure 1.

Figure 3 is a vertical longitudinal section through the attachment.

Figure 4 is a cross section on the line 4—4 of Figure 2.

Figure 5 is a similar view on the line 5—5 of Figure 2, and

Figure 6 is a detail section on the line 6—6 of Figure 2.

Referring more particularly to the drawings, the letter A designates a pump of any ordinary or well known type equipped with the usual discharge nozzle or spout B and including the vertically movable lift rod C which, in the present instance, is shown as being adapted to be reciprocated by means of a hand lever D of ordinary type pivotally mounted as shown at E on a bracket P carried by the housing or casing of the pump.

In carrying out my invention I provide a supporting frame which includes a pair of spaced parallel uprights 10 which may be formed as rods or tubes as preferred, which uprights are connected by upper and lower cross members 11, and 12 respectively held in place as for instance by means of the set screws 13 as shown. To effect mounting upon the pump, I provide a pair of plate members 14 arranged above the cross members 11 and 12 and recessed at 15 and 16 for conforming engagement against the uprights and pump casing A respectively. Located outwardly of the uprights 10 and engaging thereagainst are clamping plates 17 coacting with the plates 14 and terminating in laterally extending ears 18 through which extend the threaded ends of substantially U-bolts 19 which embracingly engage the pump casing A and which are equipped with clamping nuts 20.

Mounted on the uprights 10 at a point between the cross members 11 and 12, is a cross member 21 which may likewise be held by a set screw 22 at each side thereof. The cross piece 21 carries a stub shaft 23 on which is rotatably mounted a gear 24 here represented as of the spoke type and having one spoke formed with a plurality of holes 25 for a purpose to be described. The lower-most cross member 12 is formed somewhat as a platform and is provided with a bearing 26 through which is journaled a shaft 27 carrying a drive pulley 28 and also carrying a pinion 29 meshing with the gear 24. Quite naturally the shaft 27 may be driven in any desired manner as for instance by means of an electric motor, gas engine or other power device belted to the pulley 28.

Slidably upon the upper ends of the upright guides 10 is a cross head 30 which carries an arm 31 having a suitable hole through which the pump rod C extends. The pump rod is secured to this arm by means of a set screw 32 or the like and it

will thus be apparent that the connection of the arm with the pump rod will be made at any desired point throughout the length of the latter. The cross head further carries 5 a forward extension 33 upon which is pivoted, at 34, an elongated link 35 which has its other ends connected with a wrist pin 36 which may be engaged within any desired one of the holes 25 in the gear 24. By this 10 adjustment it will be seen that the throw of the link may be varied depending upon the desired length of stroke of the pump rod. Located between the guides 10 is a rod 36^a constituting a part of the supporting frame. 15 Surrounding the rod 36^a is a coil spring 37 which abuts against the underside of the cross head 30 and against the top of a stop collar 38 mounted on the pump rod and held thereto by a set screw 39 or the equivalent. 20 In the operation, it will be seen that when power is applied to the pulley 28 for rotating the shaft 27 the gear 24 will be rotated and as it turns the link 35 will be reciprocated and will operate to slide the cross head 25 30 up and down along the upright guides 10. Owing to the fact that this cross head is secured to the pump rod it is quite apparent that the pump will be operated in exactly the same manner as if the hand lever D were 30 used. On the downstroke of the pump rod it is quite apparent that the spring 37 will be compressed so that its subsequent expansion will operate to assist on the upstroke. In actual practice, I have discovered that a 35 pump jack constructed in this manner is highly efficient not only for the reason that the spring acts to absorb the shock of the stroke but for the additional reason that this

spring serves to assist in the upward movement and thereby lessen the strain on many 40 of the working parts. The device constitutes a very simple unit which may be easily associated with an ordinary pump and which will operate to drive the pump by means of power instead of manually in the ordinary 45 manner.

While I have shown and described the preferred embodiment of the invention, it is of course to be understood that I reserve the right to make such changes in the form, 50 construction and arrangement of parts as will not depart from the spirit of the invention or the scope of the subjoined claim.

Having described the invention, I claim:

In a device of the character described, an 55 upright supporting frame, means for mounting said frame upon a pump casing including plates disposed between the pump casing and the frame and recessed for conforming engagement therewith, clamping plates disposed outwardly of the frame, and coating with said first named plates, substantially U-shaped bolts embracingly engaging the pump casing and connected with said clamping plates, and a drive mechanism for the 60 pump rod including a cross head slideable along the frame and connected with the pump rod, a rotary element journaled on the frame, a transmission mechanism for driving the rotary element, a link connection 70 between said rotary element and cross head, and an expansion spring engaging against the cross head and against a stationary part of the pump.

In testimony whereof I affix my signature.
THOMAS DUNN.
